[57] **CLAIM**

The ornamental design for a combined telephone handset and base station, as shown and described.

DESCRIPTION

FIG. 1 is a top front perspective view of a combined telephone handset and base station therefor, showing our new design;

FIG. 2 is a top plan view thereof;

FIG. 3 is a right side elevation thereof;

FIG. 4 is a front elevation thereof;

FIG. 5 is a right side elevation thereof;

FIG. 6 is a bottom plan view thereof;

FIG. 7 is a rear elevation thereof; and

FIG. 8 is a fragmentary rear elevation with the antenna broken away in a raised position.

FIG. 1

FIG. 8

FIG. 3

FIG. 2
